UNITED STATES PATENT OFFICE

2,472,515

DIES

Paul H. Brinkoeter, San Antonio, Tex., assignor
to Ed Friedrich, Inc., San Antonio, Tex., a cor-
poration of Texas

Application July 19, 1946, Serial No. 684,967

1 Claim. (Cl. 113—49)

1

My invention relates to male and female embossing dies and it particularly has for its objects:

1. To provide a die for forming the metal sheets comprising the cooling-coil-plates disclosed in my application for patent Serial No. 684,968 filed on even date herewith.

2. To provide an embossing die composed of a plurality of like units of such size as to be interchangeable and such that units may be added or subtracted to provide for plates of different dimensions or sizes.

3. To provide a simple inexpensive set of dies and a simple means to retain the die blocks assembled on the die shoes.

Other objects will in part be obvious and in part will be pointed out hereinafter.

To the attainment of the aforesaid objects and ends invention further resides in the novel details of construction, combinations, and arrangements of parts all of which will first be fully described and then be specifically pointed out in the appended claims, reference being had to the accompanying drawings in which:

Fig. 1 is a plan view of an assemblage of male die blocks secured to a die shoe, the marginal fastenings being omitted.

Fig. 2 is an enlarged detail plan view of a portion of the same.

Fig. 3 is a view similar to Fig. 2, showing a portion of the female die.

Fig. 4 is a cross section on the plane of line 4—4 of Fig. 2 of the male and female dies.

Fig. 5 is a section of the male and female dies on the plane of the line 5—5 of Fig. 2.

Fig. 6 is a detail face view of a portion of a male die, showing a modification.

Fig. 7 is a cross section of the male die on the line 7—7 of Fig. 6 with a corresponding section of the female die that cooperates with the male die shown.

Fig. 8 is a view similar to Fig. 6 showing a further modification.

Fig. 9 is a view similar to Fig. 7 showing the male die in section on the line 9—9 of Fig. 8 and a corresponding section of the female die that cooperates with the male die shown.

Referring now to the accompanying drawings in which like numerals and letters of reference indicate like parts in all the figures, 5 and 6 represent the upper and lower die shoes respectively.

The dies comprise a plurality of male and female die blocks, all of which, except those which are used to form the inlet and outlet of the cooling-plate coil of my co-pending application, are

identical in size. Each elongated male die block 7 has an embossing protuberance 8 having rounded edges, while each female die block 10 has a recess 12 to receive the protuberance 8 of its associated die block 7. Each of blocks 7 and 10 is twice as long as it is wide and each has bevelled corners (45°) 9 with grooves 11 in the same.

The corner blocks 13 have protuberances 14, while the blocks 16 that cooperate with the blocks 13 have recesses 17. The male block 13 has a bore 15 and the female block 16 has a punch-pin 18 to cooperate with the bore 15. The corner blocks 13 and 16 are square in the embodiment shown in Figs. 1 to 5.

In the embodiment shown in Figs. 6 and 7 the corner blocks 13^a and 16^a are somewhat elongated and the protuberance 14^a and recess 17^a are so designed as to form an end-opening embossment instead of a face-opening as made by the embodiment of Figs. 1 to 5.

In the embodiment of Figs. 8 and 9 the corner blocks 13^b, 16^b are more elongated than the corner blocks of Figs. 6 and 7. The corner blocks for both the inlet and outlet of the cooling-coil plate to be made with the dies may be the short ones 13^a, 16^a or both may be the long ones 13^b, 16^b, or the short blocks may be used for the inlet and the long blocks for the outlet or vice versa, as may be found most desirable.

The several blocks are secured to their respective die shoes by means of square splines 19 inserted in the grooves 11 and secured to the shoes by the bolts 21 and spring washers 20.

The blocks are positioned on the shoes as indicated in Fig. 1, forming parallel rows of blocks side by side and a single row at one edge in which the blocks lie transversely of the plurality of rows, one block of the single row underlying two blocks in adjacent rows.

With dies measuring, say, 3" x 1½" we can make any size plate on 3" variations, either in length or width by just removing or adding additional blocks.

By moving the blocks one-half section from front to back and one-half from end to end, it is possible to make both the front and back sheets of the cooling-coil plate with one set of dies.

From the foregoing description, taken in connection with the accompanying drawings, it is thought that the construction, operation, and advantages of my invention will be clear to those skilled in the art.

What I claim is:

In embossing dies, a pair of die shoes, a set of 55 die blocks for each shoe, one set having protuber-

ances and the other set having protuberances receiving recesses, and means for securing the die blocks to their respective shoes, each die block being rectangular in form and being provided with bevelled corners having grooves parallel to the horizontal faces of the blocks, splines held in adjacent grooves of adjacent blocks, and clamping screws threaded into the shoes and passing through holes in said splines.

PAUL H. BRINKOETER.
